UNITED STATES PATENT OFFICE.

BERNHARDT JORGENSEN, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

MACHINE FOR SHAPING UPPERS TO LASTS.

1,379,923.

Specification of Letters Patent. Patented May 31, 1921.

Application filed May 18, 1917. Serial No. 169,557.

To all whom it may concern:

Be it known that I, BERNHARDT JORGENSEN, a subject of the King of Denmark, residing at Beverly, in the county of Essex and State of Massachusetts, have invented 5 certain Improvements in Machines for Shaping Uppers to Lasts, of which the following description, in connection with the accompanying drawings, is a specification, 10 like reference characters on the drawings indicating like parts in the several figures.

This invention relates to machines for use in the manufacture of boots and shoes for shaping uppers to lasts, and an object 15 of the invention is to provide in such machines improved means for insuring the correct relation of the sole or the innersole to the last in order to prevent the margin of the sole or innersole from being turned 20 back when the upper is carried inwardly over it. The invention is herein shown in its application to a pulling-over machine including means for lasting the toe portion of the shoe after the upper pulling operation, 25 but it will be understood that the invention, in its broader aspects, is not limited to machines for performing both pulling-over and lasting operations.

When the parts of a shoe are assembled 30 on a last, the innersole or the sole of the shoe, hereinafter termed generically the "sole," is usually attached to the bottom of the last at a plurality of points by tacks which are driven through the sole and into 35 the last at a distance from the margin of the sole. Since the margin of the sole, to a considerable distance inward from the edge of the last, is thus left unattached, there is danger that the margin may be up- 40 lifted from the last by the frictional engagement of the upper or of the pulling-over grippers with the edge of the sole during the upper pulling operation, or it may be by the action of lasting wipers in their 45 positioning movement relatively to the shoe preparatory to their overwiping movement, and in the subsequent operation of laying or wiping the upper over the sole the margin may consequently be turned back in 50 such manner as to prevent the upper from being properly sewed to the sole. This danger is particularly marked in the case of turn shoes, since the soles of such shoes project beyond the edge of the last bottom and

are also usually reduced in thickness at the 55 margin to provide a shoulder to which the upper is to be sewed, leaving between the shoulder and the edge of the sole a comparatively thin portion termed the "feather" of 60 the sole.

This invention provides, as an important 65 feature, a novel organization of mechanism for positioning the margin of a sole in relation to a last and for causing said positioning means to be withdrawn to permit 70 the upper to be shaped over the margin of the sole. The illustrative construction provides a hold-down for engaging the margin of the sole at the toe and means for withdrawing the hold-down inwardly over the 75 sole in a direction lengthwise of the sole. Combined with the toe hold-down, in the illustrative machine, are hold-downs for the margin of the sole at the sides of the shoe; and a further feature of the invention is 80 to be recognized in a novel construction and organization of means for positioning the margin of the sole at the toe end and at the sides.

Another feature of the invention, as embodied in a machine comprising upper pulling and fastening means, resides in a novel construction and arrangement of means for positioning the margin of the sole in relation to the last during the upper pulling 85 operation and means for withdrawing the positioning means from the margin of the sole to permit the operation of the fastening means.

As applied to a machine of the illustrative 90 type, wherein upper pulling and other operations are effected in different periods or stages of the cycle of movements of the machine, the invention provides, as a further 95 feature, a novel construction and arrangement of positioning means for engaging the margin of the sole during the upper pulling operation and mechanism for effecting a withdrawal of said positioning means in a later period of the cycle.

The various features of the invention, including certain more important details of construction and combinations of parts, will now be described with reference to the accompanying drawings and pointed out in the 105 claims.

In the drawings,—

Figure 1 is a view in side elevation of the

head portion of a pulling-over machine including mechanism in which the invention is embodied, the machine having means for lasting the toe end of a shoe,

5 Fig. 2 is a perspective view of a portion of the machine, illustrating the relation of the hold-down mechanism to a shoe,

10 Fig. 3 is a view of a portion of the machine in side elevation, and partly in vertical section, illustrating the position of the parts at the end of the upper pulling movement of the grippers,

15 Fig. 4 is a view similar to Fig. 3, showing the toe hold-down retracted, and

15 Fig. 5 shows in detail a portion of the mechanism for controlling movement of the toe hold-down.

20 The drawings illustrate the application of the invention to a pulling-over and lasting machine of a well known type particularly adapted for operation upon turn shoes, the general organization and construction of machines of this type being more fully set forth in United States Letters Patent No.

25 1,029,387, granted on June 11, 1912 upon an application of R. F. McFeely and further, in respect to certain features applicable particularly to the pulling-over and lasting of turn shoes, in Letters Patent No. 1,280,613,

30 granted on October 1, 1918, upon an invention of Orrell Ashton. In view of the disclosure in said patents, only such portions of the illustrative machine as are intimately related to the features of this invention will be

35 described herein in detail.

40 The machine has the usual toe gripper 2 and side grippers 4, these grippers being operated to pull the shoe upper over the last through the action of updraw levers 6 and 8 to which the respective toe and side grippers are connected. The machine has also a front tacker arm 10 and side tacker arms 12 carrying instrumentalities of the usual construction for laying the upper over the margin of the sole after the upper pulling operation and for fastening the margin of the upper in position on the sole, the front tacker arm in the construction shown carrying wipers 14 which are mounted to swing laterally of the shoe and operated by the inward movement of the front and side tacker arms to wipe the upper into lasted position around the toe end of the shoe. It will be understood that the operation of the machine is effected in successive stages, the machine coming to rest at the end of the first stage with the upper under tension to afford opportunity for inspection of the work and, if necessary, adjustment of the upper to position it correctly with reference to the sole and the last, as well as adjustment of the tension under which the upper is held.

45 When the machine is started a second time, it causes side clamp arms 16 to swing inward and clamp the shoe firmly at the sides,

50 these arms being operated by means of a slide 18 to which movement is imparted by a cam 20 on the main cam shaft 22. If the operation of the machine is effected in three stages, the machine will again come to a stop

70

after the clamp arms have moved into engagement with the shoe, and at this time the operator positions the wipers 14 in engagement with the toe end of the shoe in the correct relation to the shoe for movement inward to wipe the upper over the margin of

75

the sole. The toe gripper is then released from the upper, whereupon the gripper is automatically lifted out of the way of the

80

wipers and the tacking mechanism by the usual spring in the gripper operating connections. When the machine is started the

85

third time the front and side tacker arms are swung inwardly to overlay the margin of the upper and to wipe it into lasted position around the toe and fasten it, substantially in the manner explained in said prior

85

Ashton patent, the grippers receiving simultaneously an inward movement over the sole whereby they make way for the inward

90

movement of the overlaying and fastening devices and the side grippers also serving by such inward movement to overdraw the margin of the upper. During the continued

95

operation of the machine in the final stage of its cycle of operations the parts are all restored to their initial positions. It will be

100

understood that if the operation of the machine is effected in two stages only, the wipers will be positioned in engagement with the upper immediately following the upper tensioning movement of the grippers,

105

and the inward movement of the clamp arms 16 will be followed immediately by the overlaying and the fastening of the upper in the final stage. While the invention in

110

its broader aspects is not limited with respect to the precise number of stops which the machine may make, certain advantages follow the use of the invention in a machine

115

which makes one stop only, the cycle of operations thus being completed in two stages, and it will therefore be assumed that this is the manner of operation of the illustrative machine.

120

Coöoperating with the grippers in their updraw movement is a sole rest for the shoe comprising a carrier 24 mounted loosely on a horizontal shaft 26 for rocking movement about the axis of said shaft. The position of the carrier is determined by a face

125

cam 28 on the shaft 22 which engages a roll 30 on the carrier, and a spring 32 tends to rock the carrier about the shaft 26 in a direction to hold the roll 30 in engagement with the cam. Pivoted on the lower side of

125

the carrier 24 for swinging movement in substantially parallel relation to the plane of the sole are a pair of arms 34 which are normally held by a spring 36 with their

130

front ends projecting outwardly as well as forwardly in such position as to be opposed to the margin of the sole at the opposite sides of a shoe when the shoe is presented 5 to the machine. The margin of the sole at the sides of the shoe will thus be held in the correct relation to the last during the upper pulling operation. When the toe and side arms 10 and 12 swing inward to lay the upper 10 over the margin of the sole and fasten it in position, the arms 34 will yield to the inward pressure of the overlaying wipers and swing inward against the tension of the spring 36. A spring plate 38 is secured to 15 the head of the machine and arranged to bear frictionally upon the rear ends of the arms 34, the pressure of the spring upon the arms being increased by the downward rocking movement of the carrier 24 which 20 takes place, as usual, during the upper tensioning movement of the grippers. The purpose of the spring plate 38 is to hold the arms 34 with their front ends swung inward until after the side grippers have been re- 25 turned to starting position in the final stage of the cycle of operations of the machine, thus preventing the grippers from striking the arms. When the holder 24 returns to its starting position the pressure of the spring 30 38 on the arms is decreased sufficiently to permit the arms to be swung outward substantially into engagement with the side grippers by the action of the spring 36. The means including the arms 34, herein 35 shown, for positioning the margin of the sole at the sides of the shoe is more fully described and is claimed in a co-pending application of Orrell Ashton, Serial No. 129,214, filed on November 2, 1916, and as- 40 signed to the assignee of the present invention.

For carrying out the objects of this invention the machine shown is provided further with a hold-down for engaging and 45 positioning the margin of the sole at the toe end of the shoe. This hold-down comprises a plate 40 curved in substantial conformity to the edge contour of the toe end of the sole and shaped to provide a depend- 50 ing lip for engagement with the feather *a* of the sole outside of the upper attaching shoulder. The plate 40 is secured to a holder 42 which is pivoted at 44 on a slide 46 mounted in the carrier 24 for movement 55 lengthwise of the shoe. A spring 48 tends to swing the front end of the holder 42 upwardly and a screw 50 which is adjustable in the holder and is arranged to engage the slide 46 serves to determine the elevation of 60 the hold-down 40 with reference to the slide 46 and the arms 34.

When the parts of the machine are positioned for the reception of a shoe the hold-down 40 is maintained in close relation to 65 the toe gripper 2 slightly above the edges

of the gripper jaws, as shown in Fig. 2, and the hold-down remains in engagement with the feather of the sole and, in the case of a turn shoe, with that portion of the feather which projects beyond the edge of the last, 70 until after the upper has been tensioned by the operation of the grippers. In order to permit the wipers 14 to lay the upper over the margin of the sole in position to be fastened, means is provided for operating the 75 slide 46 in such manner as to retract the hold-down from the toe end of the shoe. To this end, the slide 46 is provided with rack teeth 52 which are engaged by a pinion 54 fast on the shaft 26. On one end of the 80 shaft 26 is a crank arm 56 provided with a pin 58 which engages in a slot 60 in a link 62, this link being connected at its rear end to a crank arm 64 fast on one end of a rock shaft 66 on the other end of which is a sec- 85 ond crank arm 68 connected by a link 70 to the slide 18 which serves, as hereinbefore explained, to operate the side clamp arms 16. Movement of the slide 18 toward the right (Figs. 1 and 2) to cause the clamp 90 arms to be closed against the shoe at the beginning of the second period of the cycle of operations of the machine thus serves to impart movement to the shaft 26 in a direction to retract the hold-down 40 from 95 the position in which it is shown in Fig. 3 to the position indicated by Fig. 4, this movement being effected against the tension of a spring 72 which is positioned between 100 a lug on the slide 46 and a lug on the carrier 24 and tends to move the slide forwardly. The downwardly curving lip of the hold- 105 down 40, as shown in Figs. 3 and 4, is flared outwardly on its lower face to permit the hold-down to slide readily over the shoulder of the sole in its retractive movement. With 110 the hold-down thus retracted, the wiping and tacking instrumentalities are permitted to move inward over the margin of the sole and to perform their functions in the usual manner without interference by the hold-down.

In view of the close relation between the hold-down 40 and the toe gripper jaws in the normal shoe receiving position of the parts, it is desirable that the gripper jaws, after the operation of the machine upon a shoe, shall return to their starting position prior to the return of the hold-down 40 to 115 its foremost position in order to avoid danger of interference between the gripper jaws and the hold-down. Means is accord- 120 ingly provided for maintaining the hold-down in its retracted position for a time subsequent to the return movement of the 125 slide 18 whereby the clamp arms are caused to release the shoe. To this end, a ratchet 74 is mounted upon one end of the shaft 26 and a pawl 76 is normally held by a spring 78 in position to engage the ratchet and thus 130

to hold the shaft 26 in the position to which it is moved by the operation of the slide 18 for retracting the hold-down. The slot and pin connection between the crank arm 56 and the link 62, will thus permit the return movement of the slide 18 while the hold-down is continued in its retracted position by the action of the pawl 76 on the ratchet 74. After the toe grippers have been re-
10 turned substantially to their starting position in the final stage of the cycle of operations, an upwardly extending arm 80 of the pawl 76 is engaged by a tripping member 82 to cause the pawl to release the ratchet 74 and thus permit the return of the hold-down 40 which is effected by the action of the spring 72, hereinbefore described, supplemented by the action of a spring 84 which encircles the shaft 26 close to the
15 ratchet 74 and tends to turn the shaft in the direction to move the hold-down forwardly. Conveniently the tripping member 82 is carried by a slide 85 with which machines of the illustrative type are provided for the
20 purpose of imparting advancing and retracting movement to the heel rest 86 of the machine, the retracting movement of the heel rest taking place at a time sufficiently late in the cycle of operations to permit the use
25 of the slide for operating the tripping member in the manner above described. As the hold-down is returned to its foremost position by the action of the springs, the pin 58 engages the link 62 at one end of the slot 60
30 to limit the forward movement of the hold-down. A turnbuckle 88 is provided for varying the effective length of the link 62, and by this means the limit of the forward movement of the hold-down may be varied.
35 40 It will be evident from the foregoing description that the arms 34 and the member 40 serve to insure the correct location of the margin of the sole with reference to the last at the sides and the toe end of the shoe
45 respectively, and that these members and the carrier 24 constitute a sole rest for the shoe with which the sole is engaged when the shoe is presented to the machine, the hold-down member 40, moreover, serving to
50 determine the lengthwise position of the shoe in the machine. With the shoe presented as indicated in Fig. 2 and the margin of the upper positioned within the jaws of the side and toe grippers, the machine is
55 started by the actuation of the usual clutch controlling treadle and the grippers are thus caused to pull the upper over the last, the carrier 24 being rocked simultaneously by the cam 28 in a direction to depress the
60 last within the upper through the pressure of the members 34 and 40 on the sole. The machine having come to a stop with the upper under tension, the operator makes any necessary adjustment of the position of the
65 upper on the last and of the tension of the

upper in the customary manner. The operator then releases the toe gripper from engagement with the upper and positions the wipers 14 in the correct relation to the shoe for closing movement to wipe the upper over the margin of the sole, the toe hold-down remaining in position to prevent any upturning of the edge of the sole by this positioning movement of the wipers. He then starts the machine again whereupon
70 the side clamp arms 16 are swung inward, the toe hold-down being simultaneously moved rearwardly, and the arms 10 and 12 are moved inward to lay the upper over the margin of the sole at the sides of the
80 shoe and to cause the wipers 14 to wipe the upper over the sole at the toe end, the tacking instrumentalities being operated also to fasten the margin of the upper in position upon the bottom of the sole. During the
85 inward movement of the side arms 12 the members 34 yield inwardly as hereinbefore explained. Following the tacking of the shoe, the parts of the machine are returned to their starting positions, the return of the
90 toe hold-down 40 being delayed by the action of the pawl 76 on the ratchet 74 and the return of the side hold-down members 34 being also delayed by the action of the
95 spring plate 38 on these members, in order to avoid any possibility of injury to the different hold-down members through engagement of the grippers therewith during the return of the latter to their starting positions. Finally, the pawl 76 is released from
100 the ratchet by the action of the member 82 and the hold-down 40 is advanced substantially into engagement with the toe grippers, the return of the side hold-downs 34 also being effected by the spring 36 as soon as the pressure of the spring plate 38 thereon is relieved by the upward rocking movement of the carrier 24.

Although the hold-down 40 and its operating means have been described herein
110 as arranged for operation upon the margin of the sole at the toe end of the shoe, it will be understood that the invention in its broader aspects is not limited in respect to the particular portion of the margin of the
115 sole which the hold-down is adapted to engage.

Having described the invention, what I claim as new and desire to secure by Letters Patent of the United States is:

1. In a pulling-over machine, the combination with means for pulling an upper at the toe end and at opposite sides of a last at one operation including a gripper for engaging the upper at the toe end of the
125 last and means for operating said gripper to pull the upper, of means for engaging the margin of the shoe sole to position it at the toe end of the last during the upper pulling operation, and means operatively connected
130

to said margin engaging means for moving it in a direction lengthwise of the sole after the upper has been tensioned.

2. In a pulling-over machine, the combination with means for pulling an upper at the toe end of a last and for then holding the upper under tension with the machine at rest, and means for laying the upper over the margin of a sole on the last upon a subsequent starting of the machine, of means for holding the margin of the sole in position on the last at the toe end during the upper pulling operation, and means for causing said holding means to be moved in a direction lengthwise of the sole in a period of the cycle of operations subsequent to that in which the pulling of the upper is effected. 70

3. In a pulling-over machine, the combination with a gripper for pulling an upper at the toe end of a last and end embracing wipers supported substantially in front of the toe end of the shoe to swing laterally of the shoe in wiping engagement with the upper, of means for holding the margin of the sole in position at the toe end during the upper pulling operation, and power operated means for moving said holding means inwardly from the margin of the sole to permit the operation of the wipers. 80

30 4. In a machine of the class described, the combination with means for pulling an upper over a last at a plurality of points at one operation of the machine, means for laying the upper over the margin of a sole on the last and means for fastening the upper to the sole, of means for engaging the margin of the sole to position it on the last during the upper pulling operation, and mechanism connected to said positioning means and operative in time relation to other parts of the machine for causing said positioning means to be moved away from the margin of the sole to permit the operation of the fastening means. 90

45 5. In a machine of the class described, the combination with means for pulling an upper over the toe and the opposite sides of a last and means for fastening the upper on the margin of a sole on the last at a plurality of points substantially simultaneously, of means for engaging the margin of the sole to position it on the last, and means connected to said positioning means and operated in time relation to the fastening means for moving said positioning means away from the margin of the sole after the upper pulling operation to permit the operation of the fastening means. 105

60 6. In a pulling-over machine, the combination with means for pulling an upper on a last and for then holding the upper under tension with the machine at rest, and means for fastening the upper to the sole upon a subsequent starting of the machine, of means for engaging the margin of the sole to posi- 115

tion it in relation to the last, and means connected to said positioning means and operative after the machine has been started subsequent to the upper tensioning period of the cycle of operations for withdrawing said positioning means from the margin of the sole to permit the operation of the fastening means. 130

7. In a pulling-over machine, the combination with means for pulling an upper on a last and for then holding the upper under tension with the machine at rest, and means for laying the upper over the margin of the shoe sole upon a subsequent starting of the machine, of means for engaging the feather of the sole to position it in relation to the last, and means operative after the machine has been started subsequent to the upper tensioning period of the cycle of operations for moving said positioning means inwardly from the feather of the sole. 140

8. In a pulling-over machine, the combination with separate toe and side grippers and means for operating said grippers to pull an upper on a last, of members for engaging the margin of a sole at the toe and the opposite sides of the last to prevent the margin of the sole from being lifted from the last during the upper pulling operation, and means for causing said sole engaging members to be moved relatively to the grippers in directions inward from the margin of the sole after the upper pulling operation. 150

9. In a pulling-over machine, the combination with a toe gripper and power means for operating said gripper to pull an upper on a last, of a hold-down for engaging the marginal edge of the shoe sole at the toe end during the upper pulling operation, means for fastening the margin of the upper to the sole, and automatic means for moving said hold-down inwardly from the margin of the sole to permit the upper to be fastened to the sole. 160

10. In a pulling-over machine, the combination with separate grippers constructed and arranged to engage an upper respectively at the toe end and at opposite sides of the forepart, means for operating said grippers to pull the upper, and means for laying the upper over the margin of the shoe sole, of hold-downs for engaging the margin of the sole at the toe and at the sides to position the margin relatively to the last during the upper pulling operation, the machine being constructed to cause said hold-downs to be withdrawn from the margin of the sole in time relation to the operation of said overlaying means. 170

11. In a turn shoe pulling-over machine, the combination with means for pulling an upper over the toe and the opposite sides of a last substantially simultaneously, of a hold-down constructed and arranged for en- 180

gagement with a portion of the feather of the shoe sole which projects beyond the edge of the toe end of the last to position the sole on the last during the upper pulling operation, and power operated means operatively connected to said hold-down to cause it to be moved inwardly from the margin of the sole after the upper pulling operation.

12. In a turn shoe pulling-over machine, the combination with a gripper and means for operating it to pull an upper over a last, of a hold-down constructed and arranged for engagement with a portion of the feather of the shoe sole which projects beyond the edge of the last to prevent the margin of the sole from being lifted from the last during the upper pulling operation, overlaying and fastening means and means for moving said hold-down inwardly from the edge of the sole in a direction substantially parallel to the plane of the sole to permit the upper to be fastened to the margin of the sole.

13. In a pulling-over machine, the combination with means for pulling an upper over a last and side clamp arms movable into engagement with the sides of the shoe after the upper pulling operation, of means for engaging the margin of the shoe sole to position it on the last during the upper pulling operation, and means for retracting said sole engaging means from the margin of the sole during the movement of said clamp arms to shoe engaging position.

14. In a pulling-over machine, the combination with means for pulling an upper over a last, side clamp arms, and mechanism for moving said arms inwardly into engagement with the shoe after the upper pulling operation, of a hold-down for engaging the margin of the shoe sole to position it on the last, and connections between the hold-down and said mechanism for retracting the hold-down from the margin of the sole during the inward movement of the clamp arms.

15. In a pulling-over machine, the combination with means for pulling an upper over a last, side clamp arms, and operating mechanism for moving said clamp arms inwardly into engagement with the shoe after the upper pulling operation, of a hold-down for engaging the margin of the shoe sole to position it on the last during the upper pulling operation, and means for causing said hold-down to be retracted from the margin of the sole upon a movement of said mechanism to operate the clamp arms.

16. In a pulling-over machine, the combination with means for pulling an upper over a last, side clamp arms, and operating mechanism for moving said arms inwardly into engagement with the shoe, of a hold-down for engaging the margin of the shoe sole at the toe end, and means connecting the hold-down to said operating mechanism for

the clamp arms for moving the hold-down lengthwise of the shoe.

17. In a pulling-over machine, the combination with means for pulling an upper over a last and means for laying the upper over the margin of a sole on the last, of a hold-down for engaging the margin of the sole at the toe end and hold-downs for engaging the margin at the sides during the upper pulling operation, the side hold-downs being mounted to permit them to yield inwardly from the margin during the operation of the overlaying means, and power operated means for withdrawing the toe hold-down from the margin of the sole.

18. In a pulling-over machine, the combination with upper pulling means, of a sole rest for the shoe comprising arms for positioning the margin of the sole at opposite sides of the shoe, said arms extending along the sole and being yieldable inwardly from the sides of the shoe in a plane substantially parallel to the plane of the sole, a hold-down for engaging the toe end of the sole during the upper pulling operation, and power operated means for retracting said toe hold-down from the end of the sole after the upper pulling operation.

19. In a pulling-over machine, the combination with means for pulling an upper over a last, of a hold-down for engaging the margin of the sole of the shoe at the toe end, power operated means operatively connected to said hold-down for moving it lengthwise of the shoe after the upper pulling operation, and a spring for returning the hold-down to its foremost position.

20. In a pulling-over machine, the combination with means for pulling an upper over a last, of a hold-down for engaging the margin of the sole of the shoe at the toe end, power operated means for retracting said hold-down lengthwise of the shoe after the upper pulling operation, means for locking the hold-down in retracted position, and means for releasing the hold-down to permit it to be returned to starting position.

21. In a pulling-over machine, the combination with a toe gripper and means for operating said gripper to pull an upper on a last, of a hold-down for engaging the margin of the toe end of the sole of the shoe, means for retracting said hold-down from the margin of the sole after the upper pulling operation, a spring for returning the hold-down to its foremost position, and means for locking the hold-down to prevent its return movement until after the toe gripper has been returned substantially to starting position.

22. In a pulling-over machine, the combination with means for pulling an upper over a last, of a hold-down for engaging the margin of the sole of the shoe during the upper pulling operation, means for retract-

ing the hold-down from the margin of the sole, pawl and ratchet means for retaining the hold-down in retracted position, and means for releasing the hold-down to permit its return to starting position.

23. In a machine of the class described, the combination with means for working an upper over a last, of a member for engaging the marginal edge of the sole of the shoe to position it relatively to the last, means for withdrawing said member from operative position, a spring for returning the member to operative position, and a tripping device for rendering said spring operative.

15 24. In a machine of the class described, the combination with means for working an upper over a last, of a member for engaging the marginal edge of the sole of the shoe to position it relatively to the last, means for withdrawing said member from operative position, a spring tending to return the member to operative position, locking means for retaining the member against the tension of said spring, and mechanism for causing 25 said locking means to release the member.

25. In a pulling-over machine, the combination with means for pulling an upper at the toe end and at opposite sides of a last at one operation, including an upper engaging gripper and means for imparting upper pulling movement to said gripper, of a member for engaging the marginal edge of the sole of the shoe to position it on the last during the upper pulling operation, and means 30 connected to said member for moving it inwardly in a direction substantially parallel to the plane of the sole after the upper pulling operation.

26. In a pulling-over machine, the combination with a plurality of grippers for engaging an upper on a last and means for effecting relative movement of the last and said grippers to pull the upper, said grippers being movable inwardly over the 40 bottom of the last after the upper pulling operation, of a member for engaging the marginal edge of the sole of the shoe to position it on the last during the upper pulling operation, and means connected to said 45 member for imparting to it a movement inward over the sole after the upper pulling operation.

27. In a machine of the class described, the combination with means for pulling an 55 upper on a last and for then holding the upper under tension with the machine at rest, and means for working the margin of the upper over the sole of the shoe on the bottom of the last upon a subsequent starting of the machine, of means for engaging the margin of the sole to position it on the last during the upper pulling operation, and mechanism connected to said margin engaging means for imparting to said means a 60 movement inward in a direction substan-

tially parallel to the plane of the sole in time relation to the movement of other parts of the machine.

28. In a machine of the class described, the combination with upper pulling means, 70 and end lasting wipers supported substantially opposite to the toe end of the shoe for swinging movement laterally of the shoe, of members for engaging the margin of the sole of the shoe at the toe and at opposite 75 sides of the forepart during the upper pulling operation to hold the margin of the sole in position on the last, the machine being constructed to cause said members to be withdrawn from the margin of the sole in 80 time relation to the operation of the wipers.

29. In a machine of the class described, the combination with upper pulling means and end embracing wipers, of means for operating said wipers to last the toe end of 85 the shoe, a member for engaging the marginal edge of the sole of the shoe at the toe end to position it on the last during the upper pulling operation, and means for moving said member lengthwise of the shoe 90 after the upper pulling operation.

30. In a pulling-over machine, the combination with grippers for engaging an upper at the toe and at opposite sides of a last and means for imparting upper pulling 95 movement to said grippers, of a member for engaging the marginal edge of the sole of the shoe at the toe end of the last to hold it in position during the upper pulling operation, and means operatively connected to 100 said member for moving it backward along the surface of the sole to withdraw it from operative position.

31. In a machine of the class described, the combination with means for positioning 105 an upper and a last, end embracing wipers and means for operating said wipers, of a member for engaging the marginal edge of the sole of the shoe at the toe end to position it relatively to the last, and power-operated 110 means for causing said member to be moved rearwardly from the toe end of the shoe prior to the operative movement of the wipers.

32. In a machine of the class described, the combination with power operated means constructed and arranged to pull an upper over a last and to come automatically to rest with the upper held under tension, and means for laying the margin of the upper 115 inwardly over the sole of the shoe upon a subsequent starting of the machine, of means constructed and arranged to engage the marginal edge of the sole and hold it in the correct relation to the last during the 120 upper pulling operation, and means automatically operative independently of said overlaying means to cause said margin engaging means to be moved inwardly over the sole.

33. In a machine of the class described, the combination with power operated means constructed and arranged to pull an upper over a last and to come automatically to rest 5 with the upper held under tension, and means for overlaying and fastening the upper on the margin of the sole upon a subsequent starting of the machine, of means constructed and arranged to engage the marginal edge of the sole and hold it in the correct relation to the last during the upper pulling operation, and additional means automatically operative subsequently to the upper tensioning period of the cycle of operations to cause said margin engaging means to be withdrawn from operative relation to the marginal edge of the sole to permit the upper to be overlaid and fastened.
- 20 34. In a machine of the class described, the combination with means comprising separate toe and side grippers for pulling an upper over a last, said grippers being arranged to move inwardly over the sole of 25 the shoe after the upper has been pulled, of members constructed and arranged to engage the margin of the sole at the toe end and at the sides and hold it in the correct relation to the last during the upper pulling operation, and means for causing said members to be moved out of operative relation to the margin of the sole after the upper has been pulled.
35. In a machine of the class described, 35 the combination with a gripper and means for operating it to pull an upper over the toe end of a last and to move it subsequently inward over the sole of the shoe, of a member constructed and arranged to engage the marginal edge of the toe end of the sole and hold it in the correct relation to the last during the upper pulling operation, and means for causing said member to be withdrawn from operative relation to the marginal edge of the sole after the upper has been pulled to permit the margin of the upper to be overlaid and fastened.
36. In a machine of the class described, the combination with upper gripping means 50 constructed and arranged to pull an upper over a last and then to move inwardly over the sole of the shoe, of means for engaging the marginal edge of the sole to position it relatively to the last, and means automatically operative in time relation to other parts of the machine to cause said positioning means to be withdrawn from engagement with the marginal edge of the sole prior to the inward movement of said upper gripping means.
- 65 37. In a machine of the class described, the combination with upper gripping means constructed and arranged to pull an upper over a last and then to move inwardly over the sole of the shoe, of means for engaging

the marginal edge of the sole to position it relatively to the last during the upper pulling operation, means for wiping the margin of the upper inwardly over the sole, and means automatically operative independently of said upper gripping means and in time relation to other parts of the machine for withdrawing said margin engaging means from operative relation to the marginal edge of the sole.

75 38. In a machine of the class described, the combination with means for working the margin of an upper inwardly over a sole on a last, of means for engaging the marginal edge of the sole to position it relatively to the last, and means automatically operative in time relation to other parts of the machine to cause said positioning means to be moved inwardly from the edge of the sole prior to the inward movement of said overworking means.

80 39. In a machine of the class described, the combination with means for pulling an upper over a last, and means movable inwardly over the sole of the shoe to overlay and then to fasten the margin of the upper, of means for engaging the marginal edge of the sole to position it relatively to the last during the upper pulling operation, and means automatically operative in time relation to other parts of the machine to cause said positioning means to be withdrawn from engagement with the marginal edge of the sole prior to the inward movement of said overlaying and fastening means.

85 40. In a machine of the class described, the combination with upper pulling means including a toe gripper arranged to move rearwardly over the sole of the shoe after the upper has been pulled, of a sole edge hold-down member arranged to engage the marginal edge of the sole at the toe end during the upper pulling operation, and means constructed and arranged to move said member rearwardly over the sole before the toe gripper moves rearwardly.

90 41. In a machine of the class described, the combination with means for pulling an upper over a last at the toe and the opposite sides of the forepart substantially simultaneously, means for laying the margin of the upper inwardly over the sole of the shoe, and means constructed and arranged to fasten the margin of the upper to the sole after it has been overlaid, of means for engaging the marginal edge of the sole to position it relatively to the last during the upper pulling operation, and means automatically operative in time relation to other parts of the machine to cause said positioning means to be withdrawn from operative relation to the marginal edge of the sole.

95 42. In a machine of the class described, the combination with means for pulling an upper over a last, means for wiping the mar-

- gin of the upper inwardly over the sole of the shoe, and means constructed and arranged to fasten the margin of the upper after it has been wiped inwardly, of means 5 for engaging the marginal edge of the sole to position it relatively to the last during the upper pulling operation, and mechanism connected to said positioning means and operative independently of said upper pulling 10 means and in time relation to other parts of the machine to cause said positioning means to be withdrawn from operative relation to the marginal edge of the sole.
43. In a machine of the class described, 15 the combination with means for pulling an upper over a last, means for laying the upper over the margin of a sole on the last and means for fastening the upper to the sole, of means for engaging the margin of the 20 sole to position it on the last during the upper pulling operation, and power operated means for moving said positioning means away from the margin of the sole to permit the operation of the fastening means.
- 25 44. In a machine of the class described, the combination with end embracing wipers arranged to be positioned manually against the upper of the shoe, and means for subse-

quently operating said wipers, of means for engaging the marginal edge of the sole of 30 the shoe at the toe end of the shoe to hold it on the last during the positioning of the wipers, and mechanism arranged to be operated in time relation to the operative movement of the wipers for causing said 35 edge engaging means to be withdrawn from operative position.

45. In a machine of the class described, the combination with means for pulling an upper on a last and for then holding the upper under tension with the machine at rest, 40 end embracing wipers arranged to be positioned manually against the upper while the machine is at rest, and means for operating the wipers when the machine is again 45 started, of means for engaging the marginal edge of the sole of the shoe at the toe end of the shoe to position it on the last during the upper pulling and wiper positioning operations, and mechanism operative in time relation to other parts of the machine for causing said edge engaging means to be withdrawn from operative position.

In testimony whereof I have signed my name to this specification.

BERNHARDT JORGENSEN.
